UNITED STATES PATENT OFFICE

155,972

DESIGN FOR A CANDY BOX

Inez Craven, Chicago, Ill.

Application April 29, 1947, Serial No. 138,681

Term of patent 3½ years

(Cl. D58—13)

To all whom it may concern:

Be it known that I, Inez Craven, a citizen of the United States, residing at Chicago, in the county of Cook and State of Illinois, have invented a new, original, and ornamental Design for a Candy Box, of which the following is a specification, reference being had to the accompanying drawing, forming part thereof.

Figure 1 is a perspective view of a candy box, showing my new design and illustrating the same in a closed position, and

I claim:

The ornamental design for a candy box, as shown.

INEZ CRAVEN.
